PIERRE GILLES, OF SPRINGFIELD, MASSACHUSETTS.

CARBURETER.

1,183,293.

Specification of Letters Patent. Patented May 16, 1916.

Application filed September 10, 1914. Serial No. 861,049.

To all whom it may concern:

Be it known that I, PIERRE GILLES, a citizen of Germany, and residing at Springfield, in the county of Hampden, State of Massachusetts, United States of America, have invented certain new and useful Improvements in Carbureters, of which the following is a specification.

This invention relates to carbureters for internal combustion engines and particularly to a carbureter adapted to the use of the light or heavy hydro-carbons.

The broad object of this invention is to provide a carbureter which is arranged not only to deliver mechanically atomized fuel to the carbureting chamber in the usual manner, but to also deliver with the fuel, air previously charged with fuel vapor whereby a mixture of improved combustible qualities is provided.

Another object of the invention is to provide a carbureter wherein not only the mechanically atomized fuel is provided in the usual manner, but wherein also provision is made for an air intake through the carbureter whereby air may be drawn over a relatively extensive surface of exposed fuel prior to the exit of the air into the manifold connection of the carbureter.

A further object of the invention is to provide means for priming the engine for a lighter volatile fuel contained in a separate chamber in the carbureter, which chamber and a larger chamber for the heavier fuel are connected with the atomizing devices by a common duct governed by a valve permitting the use of the fuel in either of the chambers.

The invention is clearly shown in the accompanying drawings in which—

Figure 1 is a plan view of a complete carbureter embodying the invention; Fig. 2 is a side elevation of the construction shown in Fig. 1; Fig. 3 is a vertical sectional view of the structure shown in Fig. 1 in the plane of line 3—3, Fig. 1; Fig. 4 is also a vertical section through the structure shown in Fig. 1 in the plane of line 4—4 of said Fig. 1 shown on a somewhat enlarged scale; Fig. 5 is a horizontal sectional view of the structure shown in Fig. 2 in the plane of line 5—5 of the latter, this view also being shown on a somewhat enlarged scale; Fig. 6 is an end view of the atomizing tube showing air passages on one end thereof.

Referring now to these drawings, *a* is the

body of the carbureter, to the intake end of which is fitted the bell *b*, and on the opposite end are flanges *c* for attachment to the manifold of the motor. Two chambers are 60 provided in the body of the carbureter, *d* indicating that used for the reception of the relatively volatile fuel for priming purposes and *e* indicating the larger chamber for the reception of the heavier fuel. The chamber 65 *d* is provided with an outlet passage *f*, which leads to a chamber *m* and the chamber *e* is provided with a passage *g* rectangularly arranged with respect to passage *f*. At the intersection of passages *f* and *g*, a two-way 70 valve *h* is located whereby the fuel contents from either chamber may be permitted to enter a chamber *m* in which are secured the atomizing and the vaporizing devices which will be referred to farther on. The passage 75 *f* is relatively deep with respect to its width and its cross sectional shape is indicated in dotted lines in Fig. 4. This passage may, for example, be formed by drilling several 80 holes of a diameter equal to the width of the passage one above another from the outside of the carbureter. The passage may then be closed at its outer end by the set screw of relatively large diameter, shown at the right of chamber *m* in Fig. 5. The 85 passage *g*, although not shown in cross section in the drawings, is to be understood as being identical in shape with passage *f* and the passage *g* may be formed in a similar manner and closed at its outer end by the 90 relatively large set screw, shown in Figs. 2 and 5.

By referring to Figs. 3 and 4 particularly, it will be seen that the normal fuel level is indicated by the dotted line *x*—*x*, and the 95 heavier fuel is maintained at this level in the usual manner by means of a float *o* in the chamber *e*, which float is provided with the usual needle valve *p* to govern the intake of fuel from any source of supply. 100

No float device is used in connection with chamber *d* since the fuel therein is used only for starting purposes. This chamber may be filled from its open upper end to approximately the level *x*—*x* of the fuel in chamber 105 *e*, although no particular care need be taken to have the levels of the fuels in the two chambers identical. It will be observed that the normal fuel level of the chamber *e* is in the plane of the axis of the carbureting 110 chamber *q* of the carbureter, that is to say, the passage into which the atomized fuel is

drawn on the suction stroke of the engine. It will be observed also, by reference to Fig. 4 particularly, that the plane of fuel level 5 intercepts the two passages *f* and *g* in such a manner that the fuel level is always below the top of the passages, and yet can sink to some degree without cutting off the supply from either chamber *d* or *e*. The passage *f* is thus deep enough to permit sufficient fuel 10 to be drawn for priming purposes without replenishment of chamber *d* and without the necessity of a float-controlled supply therefor. The passage *g* and that part of passage *f* used when fuel is supplied from chamber *e* 15 is also deep enough to permit the level of fuel therein to fall and remain below the normal level without interrupting the supply which condition generally occurs when the engine is running at high speeds. It will be 20 noted also that in the upper end of the cap *r*, which is fitted to the upper end of the chamber *e*, there are air passages *s* communicating with the interior of the chamber *e* above the fuel level and that the reservoir *d* is 25 open at the top to the atmosphere as shown in Fig. 3. Hence, on the suction stroke of the engine, whereby fuel will be drawn through the atomizing devices to be described into the carbureting chamber of the carburetor, this fuel will fill only the lower portion 30 of the passages *f* and *g* and only the lower portion of the chamber *m*, the upper portions of these passages and this chamber being connected to the atmosphere as here- 35 tofore described whereby air will enter the atomizing devices together with the fuel.

The atomizing devices are so constructed as to permit the discharge of mechanically atomized fuel into the carbureting chamber 40 *q* and also the air drawn through the passages *f* and *g* which air in its passage through these atomizing devices will have passed over a relatively extensive exposed area of the fuel whereby it will have become more or 45 less charged with vapor taken up from said exposed surface and, at the discharge orifice of the atomizing devices, will mix with the mechanically atomized fuel and thus enter the mixing chamber. These atomizing devices will next be described. A tube *t* extends horizontally into the carbureting chamber and, save for the aperture *v*, is closed at one end. The opposite end of this tube is flanged at *w* and bears against one wall of 55 the chamber *m*. Into this flanged end of the tube, there extends concentrically another tube *x* whose external diameter is less than the internal diameter of the tube *t*. This tube *x* has a conical end which is fitted to a 60 conical seat in the flanged end *w* of the tube *t* whereby it is held concentrically within the latter and an annular space *y* provided between the two tubes. Around the conical end of the tube *x* which bears against the 65 flanged part *w*, channels *6* are provided

whereby air and fuel from the chamber *m* may enter the annular space *y* notwithstanding the conical end of the tube is fitted closely otherwise into the part *w*. The tube *x* has a centrally located passage *7* there- 70 through which terminates axially of the aperture *v* in the tube *t*, the passage *7* being located substantially on or a trifle below the fuel level as indicated by the line *x*. To hold the two concentric tubes *t* and *x* in 75 their proper operative positions, a hollow nut *8* extends through the wall of the body of the carburetor and bears against the conical end of the tube *x* which in turn bears against the flanged end of the tube *t*. This 80 nut, when screwed into the position shown in Figs. 4 and 5, holds the parts in their operative position, and is bored through as at 9, Fig. 4, to permit the free access of the fuel to the passage *7* and also through the chan- 85 nels *6* into the lower part of the annular chamber *y* which surrounds the tube *x*. The carbureting chamber is provided with the usual regulating valve *10* or any other convenient means for regulating the passage of 90 air therethrough.

The operation of the carburetor will now be described. On starting, relatively volatile fuel, such as gasoline, for example, is 95 poured into chamber *d* through its open upper end to approximately the level *x*-*x*. The valve *h* is turned to permit fuel from chamber *d* to be drawn through passage *f* into chamber *m* and thence to the atomizing devices of the carburetor. As soon as the cylinder 100 temperature of the motor has reached the proper point to permit the use of the heavier fuel, the valve *h* is turned to cut off the supply of fuel from the chamber *d* and permit the supply contained in the chamber *e* to flow through the passage *g* to the chamber *m* and thence to the atomizing devices. The required temperature in the cylinders to 105 permit a motor to operate practically on kerosene, for example, as illustrating one of the heavier fuels, would be approximately 140 to 150 degrees which is the average vaporizing point of this fuel. If a heavier fuel were used, it would be necessary to wait until 110 the cylinder temperature were somewhat higher. Fuel having been introduced into the chamber *m*, it will rise to the level of the line *x* only; then on the suction stroke of the piston of the motor to which the carburetor is attached, mechanically atomized fuel will be ejected through the passage *7* 115 through the aperture *v* in the tube *t* and thus into the atomizing chamber *q*. At the same time, air will be drawn through the passages *6* which communicate with the annular space *y*, or at least through such passages as are located above the fuel level, and, by means of the same suction effect, this air will be drawn out through the aperture *v*. The air thus passes over the surface of the 120

fuel which is exposed thereto in the annular space *y*, and in its passage over this fuel surface becomes more or less charged with vapor evaporated therefrom. This vapor laden air mingles with the atomized jet from the passage 7 and provides a more perfectly combustible mixture than does a mechanically atomized fuel alone, especially when a fuel is used which evaporates as slowly as kerosene.

What I claim is—

1. A carbureter, comprising, a carbureting chamber, a tube closed at one end and extending horizontally within said chamber, an aperture in said tube adjacent said closed end and in communication with said chamber, a fuel supply adapted to permit the entrance of air above the level of the fuel therein, connections between said supply and said tube, the horizontal plane passing through the axis of said tube arranged to intercept said connections, the axes of the latter arranged to lie in a common horizontal plane, and means normally to maintain the level of the fuel in said supply in said first-named plane, whereby air and fuel will be drawn through said tube into said chamber, and the air will be saturated with fuel vapor prior to its entrance to said chamber.

2. A carbureter, comprising, a carbureting chamber, a tube extending horizontally within said chamber, a second tube arranged concentrically within said first-named tube, each of said tubes being formed with an aperture therein in communication with said carbureting chamber, a fuel supply, connecting means between said supply and said tubes, means to admit air to said supply above the level of the fuel therein, and means normally to maintain the level of the fuel in said supply in the plane of the axes of said tubes, the plane of fuel level arranged always to intercept said connecting means, whereby air and fuel will be delivered from said tubes into said chamber, said air being charged with fuel vapor prior to its entrance to said carbureting chamber.

3. A carbureter, comprising, a carbureting chamber, a tube closed at one end and extending horizontally within said chamber, a second tube closed at one end and mounted concentrically within said first-named tube, each of said tubes being provided with an aperture adjacent the closed end thereof which communicates with said carbureting chamber, a fuel supply, connecting means between said supply and said tubes arranged in a horizontal plane, the horizontal plane passing through the common axis of said tubes arranged to intercept said connecting means, means to admit air to said supply above the level of the fuel therein, and means normally to maintain the level of the fuel in said supply in the plane of said axis, whereby air and fuel may be delivered to

said tubes and from the apertures therein to said carbureting chamber, said air being charged with fuel vapor prior to its entrance to said carbureting chamber.

4. A carbureter, comprising, a carbureting chamber, a tube closed at one end and extending horizontally within said chamber, a second tube closed at one end and mounted within and in concentric relation to said first-named tube, each of said tubes being formed with an aperture adjacent said closed end in communication with said chamber, a fuel supply, a second fuel supply, a two-way valve, connections between each of said supplies and said valve, a connection between said valve and the open end of said tubes, each of said supplies and tubes arranged to permit the entrance of air above the level of the fuel therein, whereby fuel and air saturated with fuel vapor may be drawn from either of said supplies through said tubes to the carbureting chamber.

5. A carbureter, comprising, a casing formed with a carbureting chamber therein open to the air at one end and adapted to be connected to an engine at the other end, means to regulate the passage of air through said chamber, said casing being formed with receptacles for two kinds of fuel therein, a two-way valve, connections between each of said receptacles and said valve formed in said casing, a tube closed at one end and extending horizontally within the carbureting chamber, a second tube closed at one end and mounted concentrically within said first-named tube, each of said tubes being formed with an opening therein in communication with said carbureting chamber, a chamber formed in said casing and communicating with the open ends of said tubes, and a connection formed in the casing between said valve and said chamber, said tubes, connections and receptacles arranged to permit the entrance of air above the level of the fuel therein whereby fuel and air saturated with fuel vapor may be drawn from either receptacle into said chamber.

6. A carbureter, comprising, a casing provided with a carbureting chamber and a cylindrical chamber adjacent said carbureting chamber, a tube extending from said last-named chamber horizontally within the carbureting chamber, the end of said tube extending into the cylindrical chamber being formed with a conical seat, a second tube within said first-named tube, a conical head thereon formed with grooves therein, said head adapted to be seated in said conical seat, each of said tubes being closed at the end extending into said carbureting chamber and formed with an aperture adapted to communicate therewith, a fuel supply open to the air, connections between said supply and said cylindrical chamber, said

- 4
- 5 tubes and cylindrical chamber, arranged so that their respective axes lie in the same horizontal plane and in the plane of the normal level of the fuel in said supply and said connections arranged to be intercepted by said plane, whereby fuel and air charged with fuel vapor may be drawn into said tubes and delivered to said carbureting chamber.
- 10 7. A carbureter, having a fuel supply chamber in communication with the atmosphere above the level of the fuel therein, a carbureting chamber, an air supply for said carbureting chamber, and a nozzle in communication with the latter and also in communication at all times with the fuel supply chamber above and below the level of the fuel therein.
- 15 8. A carbureter, having a fuel supply chamber in communication with the atmosphere above the level of the fuel therein, means in said chamber to maintain the fuel therein at substantially a constant level, a carbureting chamber formed with an air intake and a nozzle in communication with the latter and also in communication with said supply chamber both above and below the level of the fuel therein at all times, all constructed and arranged so that fuel and air saturated with fuel vapor may be delivered to said carbureting chamber to mingle with the air drawn from said intake.
